MOLDED GARBAGE RECEPTACLE

Filed March 31, 1928

INVENTOR
Herbert F. Sielaff
BY John Blomstrand
ATTORNEY.

UNITED STATES PATENT OFFICE

HERBERT F. SIELAFF, OF CHICAGO, ILLINOIS

MOLDED GARBAGE RECEPTACLE

Application filed March 31, 1928. Serial No. 266,363.

My invention relates more particularly to improvements in concrete garbage receptacles which are molded into one homogeneous mass. And the objects of my improvements are to construct a molded garbage receptacle which shall be durable and serviceable for a long period of time, and which shall be weather proof, light proof, and vermin proof, and shall be economical of construction. Accessibility for thoroughly emptying the refuse from the receptacle is one of the important features of my improvements. Another important feature of my improvements is to construct the receptacle so that, particularly, the exterior corners shall be well rounded so that in shipping and rough handling they are not easily broken away.

These and other objects of my improvements will be more fully outlined in the several illustrations of the accompanying drawing and more fully described in the following specification, and more particularly pointed out in the appended claims.

In the several views illustrated in the accompanying drawing is presented the improvements as embodied in my invention.

Fig. 1 is an exterior perspective view of my invention showing some of the improvements as embodied therein.

Fig. 2 is a perspective sectional view taken on the plane A—A of Fig. 1, with the covers, and the bottom flush-out drain plugs removed, to show, more clearly, the improvements as embodied in my invention.

Fig. 3 is a section taken on the plane B—B of Fig. 2.

Fig. 4 is a section taken on the plane C—C of Fig. 2, showing the clean-out cover and the hinge water-guard in place, and the cover shown open in dotted lines.

Fig. 5 is a section taken on the plane D—D of Fig. 2, and shows that a flush-out drain hole and plug may be located in the rear wall and at the floor of the receptacle.

Fig. 6 is a sectional view showing that a flush-out drain hole and the plugs therefor may be located in the bottom of the receptacle.

Fig. 7 is a sectional view of the lower right or left hand corner of the receptacle through

one of the lateral flush-out drain holes, showing the plug therefor in place.

Similar characters refer to similar parts throughout the several views.

Referring to Fig. 1, and also to Fig. 2, will be seen the general shape and style of the exterior and the interior of my improved molded concrete garbage receptacle, 8. It will be noted that the sides, 9, and the back, 10, are vertical, and the underside of the bottom, 11, is horizontal and at right angles to the said sides and the back of the receptacle. The top, 12, however, is slightly inclined downwardly, from front to back, so that the rain and melting snow will readily run off.

Referring to the several views, Figures 1, 2, and 4, it will be seen that the front end of the receptacle has two vertical faces, 13 and 14, and an inclined face, 15, connecting them. The reason of this angular face, 15, is, that the receptacle may have its front end, 13, set close to the alley line without the danger of the hubs of vehicles scraping the front cover, 16, or marring it. The front cover, 16, is hinged to a plate, 17, which is covered by a rain guard, 18, and both 17 and 18 are secured in place over the embedded bolts, 19, by the nuts, 20. The cover, 16, is provided with a handle, or grip, 21.

A depression, 22, is formed all around the front opening, 23, into which the cover, 16, fits. The depth of the depression is such that when the cover is closed the top surface is flush with the front surfaces, 13 and 15. The depression over the opening 23, is formed to a depth equal to the thickness of both the cover, 16, and the hinge plate, 17. The lower side of the opening, 23, has an angle iron guard, 24, embedded into the concrete, as shown at 25, and 26, to guard against the concrete

from being chipped or broken by shovels, etc. Referring to Fig. 3, it will be seen that the inclined front surface, 15, is curved, outwardly and downwardly, from the sides of the depressed portion, 22, as shown at, 15A, for carrying the rain away from the sides of the cover, 16.

Located in the inclined top, 12, of the receptacle, 8, is an opening, 27. Up from the top, 12, is formed a raised portion, or ridge,

28, which extends around and forms the top of the opening, 27. A depressed cover, 29, fits over the said opening, 27, and all around the ridge, 28. U-bolts, 30, are embedded into the concrete and suitably spaced to accommodate the cover hinges, 31, secured to the cover, 29. The cover, 29, is also provided with a handle, or grip, 21.

10 To facilitate removing all of the refuse from the interior of the receptacle, the floor, 32, is inclined, both front and back, as shown at 33 and 34, and, also, at the sides, as shown at 35.

15 To facilitate cleaning the interior of the receptacle with water and germicide fluids and by flushing, flush-out drains are provided, such as are shown at 36, 37, and 38.

20 A flush-out drain, 38, shown in Fig. 7, is located in the side of the receptacle as shown in Fig. 1, as at 39. However, it may be desired to place a drain in the bottom of the receptacle, as shown at 36, in Figures 2 and 6. Also, it may be desirable to have a drain placed in the back of the receptacle, as shown 25 at 37, in Fig. 5.

30 The location of the drain, 38, is preferably placed in either of the sides, 9, or both, as shown at 39, in Figures 1 and 7. To seal the drain 38, a pair of washers, 40 and 41, are provided and clamped over both sides of the drain-hole, 38, by means of a bolt, 42, and a thumb nut, 43. A bevel shaped depression, 44, is formed in the wall, 9, as shown at 39, to provide room for the hand to grip the thumb nut, 43, and, so that the thumb nut, 43, will be within the surface, 9A, of the wall, 9, to prevent same from being broken off, and also, to permit the placing of the receptacles, closely, side by side.

45 To seal the bottom drain, 36, a conical disc, 45, is removably fitted into a conical countersink, 46, so that the top of same will be flush with the surface of the floor, 32. An ordinary wash-basin plug, 47, is provided, in addition to the said disc, to better seal the drain-hole, 36.

To seal the drainhole, 37, an ordinary conical plug, 48, is provided.

50 Referring to the several views, it will be seen that all of the exterior corners are well rounded, as at 49, to eliminate, to a great extent, the possibility of the same from being chipped, or broken off in handling; and to beautify the appearance of the receptacle as a whole. It will be noted that the interior corners are also rounded, as at 50.

55 Notwithstanding that flush-out drains have been shown as installed in the side, back, and bottom of the receptacle, it may, however, be desired to have a flush-out drain placed in the front end of the receptacle.

60 Having thus described my invention it can be readily understood that the minor details of my construction may be altered in several ways without departing from the spirit of my

invention, therefore, what I claim and desire to secure by Letters Patent is—

1. A garbage receptacle, of the character described, comprising a hollow box-like form having opposite vertical side walls, a vertical back wall, a front wall comprising upper and lower vertical wall portions joined by an intermediate inclined wall portion, a recessed opening through said inclined portion, a bottom comprising a floor having upper and lower horizontal portions joined by an inclined portion, a recessed drain outlet arranged in said lower horizontal portion, and closures therefor, an inclined top extending downwardly from said upper front wall portion to said back wall, a ridge outlined opening arranged in said top, and a hinged closure for each of said openings.

2. A garbage receptacle, of the character described, comprising a hollow box-like form having opposite vertical side walls, a vertical back wall, and a zig-zag front wall comprising upper and lower vertical wall portions and an intermediate inclined portion joining said vertical portions and having a recessed opening therein, a bar arranged across the bottom of said opening and arranged to form a portion of the recess of said opening, a series of bolts arranged in the recess above said opening, a hinge member and a hinge rain guard arranged over said bolts and there fastened, a cover for said opening hingeably mounted to said member and arranged to fit in the recess of said opening, a bottom comprising a floor having upper and lower horizontal portions and oppositely inclined portions joining said lower horizontal portion, a recessed drain outlet arranged in the lower horizontal floor portion, an inclined top extending downwardly from said upper front wall portion, a ridge outlined opening arranged in said top, U-bolts extending up from said top, and a cover for said top opening hingeably mounted in said U-bolts.
